UNITED STATES PATENT OFFICE

FRED HOWLES, OF BROUGHTON PARK, MANCHESTER, ENGLAND, ASSIGNOR TO ROYLES
LIMITED, OF IRLAM, ENGLAND, A BRITISH COMPANY

MEANS FOR DELIVERING GASES AT MEASURED RATES

Application filed August 1, 1929, Serial No. 382,823, and in Great Britain September 13, 1928.

This invention relates to apparatus for controlling the rate of flow of gases and particularly to apparatus for ensuring a slow but regular rate of flow of a gas such as 5 chlorine employed for the purification of water.

The object of my invention is to produce a simple and reliable apparatus which shall give results with a sufficient degree of accuracy for the said purpose, which shall have 10 no moving parts and in which adjustment of the rate of flow can be readily effected.

The invention comprises the combination with a tube up which liquid is raised by gas 15 delivered into the liquid, of a vessel receiving the liquid from said tube and having a siphon thereon to draw off the liquid when it attains a predetermined height therein.

The invention further comprises the arrangement of the siphon with a divergent 20 delivery portion having an air or gas vent hole therein adjacent to or at the entrance to the divergent part.

The invention further comprises the arrangement of a spreading device for liquid 25 in a connection through which the gas from the said vessel travels for the purpose of dissolving or absorbing the gas.

Referring to the two accompanying sheets 30 of explanatory drawings:—

Figure 1 is an elevation partly in section of an apparatus constructed in one convenient form in accordance with my invention.

Figure 2 is a detail view of the liquid 35 siphon shown at right angles to the Figure 1 position.

Figure 3 is an elevation partly in section showing a modified form of apparatus.

Figure 4 is a sectional view on the line 40 4—4 of Figure 3.

The same reference letters in the different views indicate the same or similar parts.

Referring to Figures 1 and 2, the gas is 45 delivered through a calibrated nozzle *a* upwards into a tube *b* immersed in liquid in the vessels *c* so that the gas acts in the manner of the known air lift system for raising liquids, to lift the liquid up the tube *b* and out of the same into a cup or vessel *d* to 50 which a siphon tube *e* is connected, the said

tube terminating in a diverging portion *f* and having a small aperture *g* therethrough adjacent to or at the entrance of the divergent part. The cup or vessel *d* has apertures *h* therein at its upper end for the delivery of the gas. The lower end of the tube *b* up which the gas and liquid rise in alternate "plugs" has a bell *i* thereon at the lower end immersed in the liquid. 55

The vessel *c* contains a liquid which in the 60 case of the proportioning of chlorine gas may be concentrated sulphuric acid.

In use, the gas under a slight head or pressure is delivered into the liquid column in the tube *b*. The liquid is raised in *b* by the 65 gas in the known manner and overflows into the cup *d*, and after a predetermined level has been reached in the latter, it siphons back to the main body of liquid by way of the siphon tube *e*. The small hole *g* which is 70 open to air or gas ensures the complete clearance of liquid from the tube when the siphoning is completed. The gas flows out of the vessel *d* into the vessel *c* and through the branch *j* to where it is required. 75

With a given gas pressure and a given size of calibrated nozzle *a*, the number of times the cup or vessel *d* fills with liquid and siphons away in any interval of time has a direct relationship to the amount of gas by volume which has been used to raise the liquid and which has passed out of the apparatus. When once the relationship of liquid raised to gas passed has been experimentally determined, the rate of delivery of gas can be 80 regulated by controlling the liquid cycles in the cup or vessel *d* by varying the inlet gas pressure. 85

The apparatus shown in Figures 3 and 4, 90 is adapted for completely dissolving or absorbing the gas delivered therein. The gas enters by the tube *a* and acts to lift liquid up the tube *b* to the vessel *d* with the siphon tube *e* thereon. The gas leaving the vessel *d* by the pipe *k* enters a vessel *m* into which liquid to dissolve the gas is sprayed through a nozzle *n* on to a disc *o* whereby it is spread in a thin film to fill the vessel *m*. The liquid leaves *m* by the pipe *p* and passes through 95 the vessel *c* which receives the delivery from 100

the siphon *e*, to the outlet branch *q*. The tube *r* on the vessel *c* acts to prevent the formation of a vacuous condition in such vessel by admitting air thereto. The operation of this apparatus is substantially the same as the apparatus shown in Figures 1 and 2, but some of the gas will be absorbed in the tube *b*; but the ratio of gas absorbed in *b* to the total gas which passes through the apparatus will not vary sufficiently to affect the results or calculations based on the rate of filling and emptying of the vessel *d* before described. Further from the known solubility of the gas, the amount dissolved in the liquid raised can be calculated.

What I claim is:—

1. A method of ascertaining and regulating the rate of delivery of a gas consisting in utilizing said gas for raising a liquid in the manner of an air lift pump measuring the number of times a predetermined quantity of the liquid is raised by the gas in any predetermined interval of time and collecting the gas used in raising the liquid and which separates from the latter.

2. An apparatus for delivering a gas at a measured rate, comprising the combination with a tube up which liquid is raised by the gas which is delivered into the liquid in said tube, of a vessel receiving the raised liquid from said tube, a siphon upon said vessel to draw off the liquid when it attains a predetermined height, and means receiving the gas used in raising the liquid and which separates from the latter.

3. In apparatus as claimed in claim 2, the arrangement of the siphon with a divergent delivery portion and a gas vent hole adjacent to or at the entrance to the divergent part of the siphon.

4. In apparatus as claimed in claim 2, means for receiving the liquid from the siphon, a tube having an enlarged part and leading from the top of the vessel with the siphon thereon to said means into which the liquid siphons, and a liquid inlet nozzle and liquid spreader adjacent to the said nozzle in the enlarged part of the said tube to effect the absorption by the spread liquid of the gas delivered into said tube.

5. An apparatus for use in ascertaining and regulating the rate of delivery of a gas, comprising, in combination, an outer vessel having a gas outlet, an inner vessel having a gas outlet in the top thereof, a tube extending up into said inner vessel from the lower part of said outer vessel, a gas inlet tube extending through said outer vessel into the said tube leading up into the inner vessel, and a siphon upon said inner vessel emptying the contents thereof when they reach a predetermined height into the outer vessel.

6. An apparatus for use in ascertaining and regulating the rate of delivery of a gas,

comprising, in combination, a liquid and gas receiving vessel, a siphon upon said vessel for emptying the said vessel intermittently, a second vessel receiving the liquid from the siphon, a tube connecting the second vessel to the first mentioned vessel, means injecting the gas into the liquid in said tube whereby both liquid and gas are elevated to the first mentioned vessel, a further tube extending between the top of said first mentioned vessel to the second mentioned vessel to receive the gas which separates from the elevated liquid, means injecting liquid into said gas to absorb the same, and an air venting and a liquid overflow connection to said second vessel.

In testimony whereof I have signed my name to this specification.

FRED HOWLES.
